UNITED STATES PATENT OFFICE.

PAUL W. KNAUF, OF PHILADELPHIA, PENNSYLVANIA, ASSIGNOR TO THE ELECTRICAL LEAD REDUCTION COMPANY, OF SAME PLACE.

ELECTROLYTIC APPARATUS.

SPECIFICATION forming part of Letters Patent No. 669,752, dated March 12, 1901.

Application filed July 17, 1900. Serial No. 23,898. (No model.)

To all whom it may concern:

Be it known that I, PAUL W. KNAUF, a citizen of the United States, residing at No. 4448 North Uber street, in the city and county of 5 Philadelphia, State of Pennsylvania, have invented certain new and useful Improvements in Electrolytic Apparatus, whereof the following is a specification, reference being had to the accompanying drawings.

10 My invention relates to an apparatus wherein a series of receptacles is employed to contain substances which are to be electrolytically treated or acted upon by the products of electrolysis; and the main features 15 of improvement comprise both the peculiar construction of the unit of the series and their combination in an organized group which occupies a minimum of space and is easy of manipulation, while at the same time 20 affording a complete control of the gaseous products of electrolytic action.

Referring to the drawings, Figure 1 is a top or plan view of a preferred form of receptacle constituting a unit of the series. Fig. 2 25 is a vertical central section on the line 2 2 of Fig. 1 through a series of two such receptacles. Fig. 3 is a vertical central section on the lines 3 3 of Fig. 1 through a single receptacle. Fig. 4 is a top or plan view, and 30 Fig. 5 is a side elevation, of a group composed of four stacks of said receptacles arranged in position. Fig. 6 is a view in perspective of the insulating-shield. Figs. 7, 8, and 9 are 35 partial sectional views illustrating modifications of the form of the receptacle.

In the instance selected for illustration I shall describe an apparatus adapted for the electrolytic reduction of lead ore.

In the type shown in Figs. 1 to 6 the receptacle A (preferably cast from antimonial lead) 40 has the general shape of the frustum of a cone, the outer surface of the bottom also tapering downward slightly toward the center. An external annular flange B is formed 45 around the side or wall of the receptacle and projects slightly beyond the periphery of the upper edge thereof, said flange terminating in a downwardly - turned lip b. Vertical strengthening-ribs C are formed radially at 50 intervals upon the outside of the receptacle, extending upward from the flange B to the

top. The relation of the total diameter at the flange to the total diameter of the top of the receptacle is such that when one receptacle is superimposed upon another, as shown in 55 Fig. 2, the top edge of the lower one is snugly seated within the downwardly-turned lip of the flange, which prevents displacement, the conical walls of the receptacles affording an interspace between the adjacent surfaces. At 60 points preferably diametrical in the flange B orifices d d' are formed, for a purpose which will hereinafter be described. A shield E, of insulating material, such as rubber, is arranged to fit snugly around the inside surface of the wall of the receptacle, extending from the top to the bottom thereof, and is provided with an outwardly-projecting rim e, which covers the top edge of the wall, and hence is interposed between it and the flange 70 of the next receptacle, so as to insulate one from the other. At diametrical points and coincident with two of the ribs C (which are preferably made larger than the rest) horizontal holes D are formed to permit the insertion of tongs or other convenient lifting devices, (not shown,) whereby the receptacle 75 may be lifted and the contents dumped by tilting, as upon trunnion-bearings. The receptacles are combined by superimposing 80 them in stacks, as shown in Fig. 5, the lowest member being supported upon non-conducting legs, (indicated at H,) and four of such stacks being preferably grouped about a central gas-duct F. Communication between 85 this central duct and each one of the receptacles is effected by flexible tubes f f' f' f'', preferably of rubber, said tubes being inserted in the orifices, such as d, before indicated. The other orifices, such as d', are intended to 90 be used for replenishing the contents of the receptacles during working and of course should be closed by a stopper of rubber or other proper material. It will thus be seen that the superimposed receptacles, with the 95 interposed rims of the shields, form tight joints with one another, and a series of sealed chambers insulated from one another is obtained, each chamber communicating only with the central gas-duct.

100 I will now proceed to describe the use of the apparatus in connection with the electrolytic

reduction of lead ore, such as galena or sulfid of lead. The ore to be reduced is placed in the bottom of the receptacles to a depth which leaves a short interval between the top of the 5 mass and the under surface of the next receptacle above it, and the electrolyte, consisting of one part of pure sulfuric acid to ten of water, is then poured in to a level higher than the bottom of such next receptacle. The con- 10 ducting-wire P from the positive pole of the source of electricity is connected with the top receptacle of one stack, preferably by clamping it upon one of the ribs C. The bottom receptacle of this stack is electrically connected to the top receptacle of the next stack, and so on, the circuit being finally completed at the bottom receptacle of the last stack, which is connected with the negative pole by the wire N. The shields E by insulating the 15 side walls of the receptacles restrict the current to a substantially vertical path through the mass of ore, and thus prevent the ineffectual short-circuiting which would otherwise occur. The sulfureted hydrogen gas which 20 results from the foregoing operation passes out through the tubes f, &c., into the central gas-duct, by means of which it is conducted to any proper point of discharge for utilization or otherwise. The tapering under surface of the receptacle facilitates the escape 25 of the gas rising from the ore.

When it is desired to remove the contents, the top receptacles of the respective stacks can be successively lifted off and dumped by 30 tilting upon their trunnion-bearings, the other receptacles of the series remaining sealed, as above.

In the form shown in Fig. 7 the general configuration of the receptacle is the same as that 40 just described; but instead of providing the flange B' with a lip upon its extreme periphery I obtain a similar result by means of the downwardly-projecting rib b', which engages with the inner face of the top of the subjacent 45 receptacle.

In the type shown in Figs. 8 and 9 the necessary reduction in diameter at the lower portion of the receptacle is obtained by constructing the side or wall with an offset a, 50 which also affords the bearing - surface for seating the receptacle upon the next one of the series. This offset may be provided with a downwardly-projecting lip, such as a', or may have a countersunk bearing-surface in 55 the form of a channel, such as a'', to afford a seat for the top edge of the next receptacle. In this instance the gas-orifices a''' are located in the wall above the offset, and corresponding holes are formed through the insulating- 60 shields E⁸ and E⁹, respectively.

I have shown these variations of detail to illustrate a few of the embodiments which the invention permits; but I of course do not limit my claims to the precise types shown. It 65 is only necessary that the receptacles shall be capable of superimposition in vertical series

with proper interspaces for ore and electrolyte and that a proper bearing-surface shall be afforded for securing a close joint between the top edge of one receptacle and the region of contact with the next one, the combination being such as to permit the proper location of gas-orifices.

I claim—

1. The combination, of a series of super- 75 posed metallic receptacles, each having its lower portion of less diameter than the upper edge, and each having an exterior peripheral seat arranged below said upper edge but conforming throughout its whole extent with 80 such edge, said receptacles being respectively provided with external gas-escape orifices adjacent to said seat, whereby a series of wholly-isolated chambers having individual escape-orifices is formed, substantially as set forth. 85

2. An element for an electrolytic series consisting of a metallic receptacle having its lower portion of less diameter than its upper portion; an exterior peripheral flange arranged below its edge, said flange being provided with 90 an orifice; and a series of radial strengthening-ribs adjacent to said flange, substantially as set forth.

3. The combination, with an element for an electrolytic series consisting of a metallic receptacle having its lower portion of less diameter than its upper portion, and an exterior peripheral seat arranged below the upper edge; of an insulating-shield fitting against the side wall of the cell and extending outward over the top edge thereof, substantially as set forth. 95

4. An element for an electrolytic series consisting of a metallic receptacle having its lower portion of less diameter than the upper portion, in combination with an exterior peripheral seat arranged below its upper edge, and means, substantially as set forth, for providing trunnion-bearings, whereby said receptacle may be tilted to discharge its contents. 105

5. The combination of a gas-duct; a series of superimposed metallic receptacles, each having an exterior peripheral seat adapted to engage with the top edge of the subjacent receptacle, and an orifice adjacent to said 115 seat; and a series of tubes leading from said orifices to said gas-duct, substantially as set forth.

6. An element for an electrolytic series consisting of a metallic receptacle having its lower 120 portion of less diameter than the upper portion and having a bottom surface which is inclined upward radially from the center to the outer periphery, in combination with an exterior peripheral seat arranged below the upper edge, and an orifice adjacent to said seat, 125 substantially as set forth.

PAUL W. KNAUF.
